UNITED STATES PATENT OFFICE.

CHARLES WARREN, OF IPSWICH, COUNTY OF SUFFOLK, ENGLAND.

MACHINE FOR MASHING POTATOES, &c.

SPECIFICATION forming part of Letters Patent No. 399,587, dated March 12, 1889.

Application filed December 22, 1887. Serial No. 258,702. (No model.) Patented in England October 29, 1887, No. 14,722; in France February 7, 1888, No. 188,596, and in Belgium February 7, 1888, No. 80,559.

To all whom it may concern:

Be it known that I, CHARLES WARREN, a subject of the Queen of Great Britain, residing at Ipswich, in the county of Suffolk, England, 5 have invented a new and useful Improved Machine for Mashing Potatoes and Crumbling Bread and for Similar Purposes, (Letters Patent for which were granted me in Great Britain October 29, 1887, numbered 14,722; in France 10 February 7, 1888, numbered 188,596, and in Belgium February 7, 1888, numbered 80,559,) of which the following is a specification.

My invention relates to machines for mashing potatoes and other vegetables and for crumbing bread; and it consists in a certain improved construction of the same, fully set forth in the following specification and claim.

In the accompanying drawings, illustrating my invention, Figure 1 is a front elevation of 20 my improved machine. Fig. 2 is a side elevation of the same. Fig. 3 is a vertical section on line $x-x$, Fig. 1.

Similar reference-letters indicate identical parts throughout.

25 a is the barrel or cylinder of the machine, in which is located a spiral compressor, b , mounted upon a shaft, c , which is journaled in a bearing, d , at one end of the barrel. The outer extremity of the shaft c is provided with 30 a handle, g , by which the compressor is rotated.

The barrel a is supported by a standard, e , and is provided with a hopper, f , through which the material to be operated upon is introduced into the machine. The bearing, standard, and hopper are preferably formed integral with the barrel.

i is a disk of wire-gauze or other suitable material secured to a ring, k , which surrounds 35 the cylinder. To hold this disk in position, I provide a ring, j , which also encircles the cylinder, and has a flange, j' , extending over the

end of the cylinder for the purpose of clamping the disk i . The disk j is provided with slotted ears n , which receive swivel-bolts l , 45 attached to the cylinder, as shown in Figs. 1 and 2. To fasten the disk over the mouth of the cylinder, the ring k , to which the wire disk is attached, is placed in position and the ring j placed over it. The bolts l are then slipped 50 into the slotted ears n and the nuts m screwed down until they rest upon the flange j' . A further turning of the nuts forces the rings j and k inward upon the cylinder and stretches 55 the wire tightly across the mouth of the cylinder, in which condition it is firmly secured by the flange j' , clamping it against the cylinder. By this means I secure what might be termed a "drum-head tension," which is very 60 desirable in a machine of this character, as it is necessary that the wire-gauze should be drawn very tightly across the mouth of the cylinder to insure the best results.

It will be seen that the forcing of the ring k inward upon the cylinder stretches the wire 65 before it is clamped in position.

What I claim, and desire to secure by Letters Patent, is—

In a machine for mashing vegetables and other substances, the combination, with the 70 barrel or cylinder a , of the wire-gauze provided with a ring, k , extending around the cylinder, of the ring j , also extending around the cylinder, having a flange, j' , extending over the end of the cylinder and being provided 75 with slotted ears, and the swivel-bolts secured to the cylinder and adapted to engage the slotted ears, whereby the wire-gauze is stretched tightly across the end of the cylinder and clamped, substantially as described. 80

CHARLES WARREN.
